ATTORNEY.

UNITED STATES PATENT OFFICE.

DE WANE B. SMITH, OF DEERFIELD, NEW YORK.

DESIGN FOR A BODY FOR SPRAYERS.

SPECIFICATION forming part of **Design No. 29,292, dated August 30, 1898.**

Application filed August 3, 1898. Serial No. 687,649. Term of patent 3½ years.

To all whom it may concern:

Be it known that I, DE WANE B. SMITH, a citizen of the United States, and a resident of the town of Deerfield, county of Oneida, 5 and State of New York, have invented and produced a new and original Design for a Body for Sprayers, of which the following is a specification, reference being had to the accompanying drawings, forming a part hereof.

10 Figure 1 shows a perspective view of a sprayer-body of my design. Fig. 2 shows a side elevation, and Fig. 3 shows an end view.

As shown in the drawings, the leading or material feature of my design consists of an 15 elongated cylindrical body portion 1 and the dependent cross-cylinder portion 2 in connection with tubes 3, projecting from the side of

the cross-cylinder portion to a position on the end of the main-body cylindrical portion, as shown; and the design consists in the form 20 and relative arrangement of the various parts mentioned.

Having described my invention, what I claim as new, and desire to secure by Letters Patent, is—

The design for a body for sprayers as herein shown and described.

In witness whereof I have hereunto affixed my signature, in the presence of two witnesses, this 27th day of July, 1898.

DE WANE B. SMITH.

Witnesses:

E. WILLARD JONES,
SARAH A. BROWN.
